(57) **CLAIM**

The ornamental design for a shelving unit, as shown and described.

DESCRIPTION

FIG. 1 depicts a front, left, upper perspective view of a shelving unit showing our new design.

FIG. 2 depicts a front view of the shelving unit with a beam of the shelving unit disassembled from a post of the shelving unit.

FIG. 3 depicts a front, left, upper perspective view of the beam.

FIG. 4 depicts a front, right, lower perspective view thereof.

FIG. 5 depicts a front view thereof.

FIG. 6 depicts a left view thereof.

FIG. 7 depicts a right view thereof.

FIG. 8 depicts a top view thereof.

FIG. 9 depicts a bottom view thereof.

FIG. 10 depicts a back view thereof.

FIG. 11 depicts a front, left, upper perspective view of the post.

FIG. 12 depicts a front, right, lower perspective view thereof.

FIG. 13 depicts a front view thereof.

FIG. 14 depicts a back view thereof.

FIG. 15 depicts a left view thereof.

FIG. 16 depicts a right view thereof; and,

FIG. 17 depicts a top view thereof.

The dash lines represent portions of the article forming no part of the claimed design. The dot-dash lines represent boundaries of the claimed design.
